UNITED STATES PATENT OFFICE.

RAY H. CLIFTON, OF EAST PERU, IOWA.

THROTTLE-VALVE.

1,308,842.

Specification of Letters Patent. Patented July 8, 1919.

Application filed September 14, 1916. Serial No. 120,108.

To all whom it may concern:

Be it known that I, RAY H. CLIFTON, a citizen of the United States, residing at East Peru, in the county of Madison, State of Iowa, have invented certain new and useful Improvements in Throttle-Valves; and I do hereby declare the following to be a full, clear, and exact description of the invention, such as will enable others skilled in the art 10 to which it appertains to make and use the same.

This invention relates to throttle valves, and has particular reference to throttle valves which are adapted for use for automobile engines.

The invention has for its primary object to provide an improved throttle valve of a type that may be operated to instantaneously cut off the gas supply to the engine, so that driving power of the latter may be eliminated without throwing out the clutch or shutting off the ignition switch. It is a well known practice among automobile drivers to "cut off the engine" in going down hill by cutting off the ignition switch or throwing out the clutch. When the ignition switch is cut off, the clutch, of course, still connects the engine and the drive shaft, so that when coasting down hill the engine 20 runs idly and acts in a certain measure as a brake. In following this practice, care must be taken, when the bottom of the hill is reached and the ignition switch is again closed, that the gas which has passed 30 through the engine and into the muffler does not become ignited, and exploding in the muffler destroy the latter. My invention permits the cutting off of the motor instantaneously without the necessity of throwing 35 out the clutch or cutting off the ignition system, so that the desirable braking action of the engine may be retained without danger of destroying the muffler.

My invention contemplates the provision 45 of a kind of device or throttle valve which is interposed between the carbureter and the engine, as in the intake pipe. The device, generally speaking, consists of a casing in which is formed a chamber which receives a 50 comparatively thin wide blade-like valve having an opening which, when in position, registers with the gas passage to admit the gas to pass therethrough and which in another position cuts off the gas passage entirely, so that the gas does not reach the engine, which is therefore run idly, or else

stops. The device may be so connected as to be operated either by a foot pedal or by a hand lever upon the steering wheel or steering post.

With the above objects in view and such other objects which may hereinafter appear, my invention will now be fully set forth and described, reference being had to the accompanying drawings.

In the drawings:

Figure 1 is a part elevational and part sectional view of an automobile showing the application of my invention thereto,

Fig. 2 is a vertical section through the 70 throttle valve,

Fig. 3 is a section on line 3—3 of Fig. 2,

Fig. 4 is a section on line 4—4 of Fig. 2, and

Fig. 5 is a detailed view of the actuating 75 mechanism.

Referring more particularly to the drawings, 1 indicates a carbureter and 2 the intake pipe of an automobile engine. Interposed between the carbureter 1 and the 80 intake 2 is a valve casing 3 which carries the cover plate 4. Preferably, the casing 3 is bolted to the coupling flange 5 of the carbureter and the cover plate 4 is secured by means of the flange 6 of the intake. The 85 opposing faces of the cover plate 4 and the casing 3 are recessed to snugly receive therebetween the valve plate 7. The recess 8 within which the valve plate 7 operates is an elongated passage way and slidably receives the valve plate 7 with a gas tight fit. The body or casing 3 and the cover plate 4 are provided with the registering passages 9 which register with the intake 2 and the carbureter 1, said passages 9 lying in the 90 path of movement of the valve plate 7. The valve plate 7 is provided with a circular opening 10 which registers in one position of the valve plate with the passages 9. The casing 3 is provided with a vertical cavity 100 11 which communicates with the recess 8, and provides for the operation of a stem 12. The stem 12 is a right angled element, one of whose arms 13 is secured to the lower face of the valve plate 7 and has its other arm projected through an opening 14 in the end of the casing 3. A packing 15 held in place by a bushing 16 makes a gas tight passage around the stem 12. It should be noted that the valve plate is fitted within the recess 8 in such a manner that it prevents the passage of gas from the recess into the cavity 110

11. The opening 10 does not come into communication with the cavity 11 at any time.

In Fig. 1, 17 indicates a foot pedal which extends through the foot board of the automobile body and is carried by a bracket 18 secured to the lower side of the foot board, or in any other suitable place. The bracket has two overturned arms through which the shank of the foot pedal projects, and surrounding said shank is a coil spring 19 which bears between one of said overturned arms, and a collar 20 adjustably secured upon the shank of the foot pedal 17. Below the overturned arm of the bracket 18, the foot pedal is furthermore provided with an adjustable collar 21 which provides a stop to the upward movement of the foot pedal upon its return to normal position. The lower end of the foot pedal connects to a bell crank lever 22 whose opposite arm connects to the extended stem 12 of the valve plate 7.

This mechanism between the foot pedal and the valve stem is an obvious mechanical expedient and will necessarily be changed where the device is applied to automobiles in which the throttle must be located at other points or where the carburetor is upon the opposite side of the engine from the steering wheel. The operation of the mechanism is obvious, but it should be noted that it provides a means for immediately and completely cutting off the gas supply so that the engine may run idly where circumstances make it desirable, as when the car is coasting down hill. By making it possible to cut off the gas supply instead of the spark-

ing mechanism, all danger of blowing out the muffler is obviated,—and it becomes unnecessary to change the gears or disconnect the clutch when it is desired to slow down quickly.

The device is simple and can be applied to cars of any make, either in building, or already in operation.

What I claim is:—

A throttle valve for the fuel feed conduit of an automobile engine, including a relatively thick plate provided with a port transversely therethrough, a relatively thin plate secured to one side of the first named plate and provided with a port registering with the port of the first plate, said plates being formed to provide a slide plate channel therebetween, a slide plate mounted in said channel and provided with a port adapted to register with the ports of the plates, the thick plate being provided with a recess at one side of its port extending longitudinally in the direction of movement of the slide plate and opening into the slide plate passage, an actuating stem slidably passed through one end portion of the thick plate into the recess and having its end therein laterally directed and secured to the slide plate and a packing member surrounding the stem and threaded in the thick plate.

In testimony whereof, I affix my signature, in the presence of two witnesses.

RAY H. CLIFTON.
